UNITED STATES PATENT OFFICE.

SETH WILLIAM BABBITT, OF MERIDEN, CONNECTICUT, ASSIGNOR TO THE INTERNATIONAL SILVER COMPANY, OF MERIDEN, CONNECTICUT.

DESIGN FOR A CANDELABRUM.

SPECIFICATION forming part of Design No. 35,453, dated December 17, 1901.

Application filed October 19, 1901. Serial No. 79,307. Term of patent 7 years.

To all whom it may concern:

Be it known that I, SETH WILLIAM BABBITT, a citizen of the United States, residing at Meriden, in the county of New Haven and State of Connecticut, have invented and produced a new and original Design for a Candelabrum; and I do hereby declare the following to be a full, clear, and exact description of the same, reference being had to the accompanying drawings, forming a part thereof.

This invention relates to a new and original design for candelabra; and it is embodied in the shape, configuration, and general ornaments presently to be described, and shown in the accompanying drawings.

In the drawings, Figure 1 is an elevation of a candelabrum embodying the invention; and Fig. 2 is a plan view of the same, showing the upper central portion removed for the purpose of illustrating the general arrangement of the arms.

The design, as illustrated, comprises, generally speaking, a base, a standard, a series of arms, and a central holder, the base portion being substantially of hexagonal formation, with slightly-curved edges between the points of angle and an overhanging cap or top portion. The surface of the base is divided into scroll parts or fields by scroll-shaped beadings, and the space between the beads directly below the overhanging portions is occupied by suitable pinnated designs. Mounted on the center of the base is the standard, having a circular portion, from which extends, on an upward curve, the body portion, which in turn is curved inwardly and somewhat elongated to form a stem terminating in an outwardly-flared portion. The body and stem of the standard are divided into equal fields by scroll-formed beads, the lowermost beads terminating in lobe-shaped extensions, between which on the intervening space are pinnated representations. The upper portion of the standard is fancifully formed and has

on the fields between the beading suitable 45 fanciful bead effects. Springing from the top of the standard are a series of curved arms, four in number. These arms are curved horizontally in a graceful outward curve and bent downwardly, terminating in lobes and carrying on their sides substantially U-shaped extensions, the inner ends of which are branched and rounded, while the outer ends carry suitable finishing points or projections, which in turn support the candle-holders. These holders or receptacles are formed with outwardly-curved lower portions and inwardly-curved upper portions, the face of which is divided by suitable fanciful ribs or beads of scroll formation. The spaces between the ribs or beads at or near the center of the holder are occupied by pinnated designs or representations. Surmounted on the holder are the projecting flanges shown, and below the holder are similar flanges. These flanges are substantially dish-shaped and, as shown in Fig. 2, have the spray design at their edges. Springing from the center of the standard is the central stick or holder, of a design similar to those heretofore described, the same being supported on a pedestal, the lower part of which is fashioned to represent scrollwork.

The essential features of the design reside more particularly in the general arrangement and shape of the various parts referred to, 75 irrespective of the minute details.

Having thus described the invention, what I claim as new, and desire to secure by Letters Patent, is—

The design for a candelabrum substantially 80 as shown and described.

In testimony whereof I affix my signature in presence of two witnesses.

S. WILLIAM BABBITT.
